Robt. W. Pearson
attorney.

UNITED STATES PATENT OFFICE.

FRANCIS S. INCO, OF LOS ANGELES, CALIFORNIA.

PORTABLE BED.

Application filed February 23, 1926, Serial No. 89,988. Renewed January 3, 1928.

My invention relates to folding beds and more particularly pertains to sanitary beds of all metal construction, designed to be mounted on rollers, and when folded up, to be moved into a closet and kept out of sight.

In constructing beds of this type it is important that they be as narrow in side elevation as possible in order to economize in closet space and at the same time be steady and rigid when moved out of the closet and utilized.

Heretofore it has been found necessary that the head piece of the bed be heavily weighted in order that it will not tilt or lift upwardly when the bed is lowered, as the base space must necessarily be narrow.

It is the object of my present invention to provide a construction which will serve to overcome the above recited disadvantages, and at the same time preserve the narrow base span and obviate the necessity of weighting the bed in any manner.

A further object is to provide a bed which will be perfectly counterbalanced at all times while being manipulated into or out of usable position.

Still another object is to provide means for preventing the structure from rolling backward or forward while the mattress is being lowered or lifted.

The above and other objects of my invention will be more fully disclosed in the following specification, and by referring to the annexed drawings, in which:

Figure 1 is a side elevation of the bed as it would appear when in a lowered position.

Figure 2 is a rear view of a portion of the same.

Figure 3 is a longitudinal section through the head portion of the bed as it would appear when the brace legs are let down.

Figure 4 is a longitudinal section through the head portion of the bed as it would appear when closed and out of use.

Figure 5 is a similar view showing the bed as it would appear when open and ready for use.

In the construction of the bed, opposite sides are identical, they being tied together by suitable spacing bars which will be hereinafter mentioned, so a description of one side will serve as a description of the other.

Referring to the drawings, 10 and 11 represent oppositely disposed head leg members, which are U-shaped in form, and preferably made of round tubing, and comprise the horizontally disposed bars 12 and the depending legs 13 and 14 which are equipped with rollers 15 and 16. The leg members 13 and 14 are prevented from spreading apart by means of the angle irons 17 and 18, the lugs of which are secured thereto, these constituting the main frame of the bed.

Pivoted to the angle irons 17 by means of bolts 19 are the bed rails 20 and 21, which are tied together at their head ends by means of a transverse angle iron bar 22, goose neck fittings 23 and 24 being interposed between the bars and the rail ends.

The foot ends of the rails 20 and 21 are provided with goose neck fittings 25 which are held properly spaced apart by the bars 26 and 27 as shown in Figure 1 of the drawings. A bed spring 28 is stretched between the two sets of goose neck fittings to form the usual platform for the bed mattress, (not shown).

The foot legs of the bed are formed of a U-shaped piece of tubing 29 and are foldably secured to the bed rails by means of hinge straps 30 and 31.

Leg bars 32 and 33 are respectively pivoted to the angle irons 17 and 18 at one of their ends by means of pins 34 and are provided at their opposite ends with rollers 35 adapted to rest upon the floor when the bed is down and just before the bed is lowered, and are tied together by the transverse angle bar 36. Pivoted at 37 to the brace legs, at one of their ends, are brace bars 38, which are slotted at their opposite ends, as at 39. Pins 40 project from the angle irons 18 and pass through the slots 39, thus permitting the brace bars 38 to have a sliding movement. The bars 33 and 38 form a toggle truss for the support of the bed frame when the bed is lowered as clearly shown in Figure 5 of the drawings.

A head board 41, which is preferably formed of tubing bent into the shape of a U, is provided, and the legs of the same are pivoted at 42 to the extension arms 43 secured to the goose neck members 23 and 24.

The ends of the link brace straps 44 are pivoted at 45 to the legs of the head board 41 and their opposite ends have pivoted to them at 46 the link members 47, said link straps 44 being pivoted intermediate of their ends at 48, to standards 49 secured to the fixed angle irons 17. Pivoted at 50 to the brace legs 32 and 33 are link brace straps 51, the opposite ends of which are pivoted on the pins 52 projecting from the link members 47, and also pivoted on the pins 52 intermediate of their ends are the cross bars 53. Interposed between one of the ends of each of the crossbars 53 and the leg bars 32 and 33 are the springs 54, shown more clearly in Figure 5 of the drawings, the spring is broken out for sake of clearness. Interposed between the opposite ends of the cross bars 53 and the goose neck members 23 and 24 are springs 55, and interposed between the ends of the link members 47 and the goose neck members 23 and 24 are the springs 56.

It will be noticed by reference to Figure 5 of the drawings that the entire bed occupies exceptionally narrow space, and that the bed rails constituting the platform, are locked in a vertical position by means of the transverse angle bar 36 secured to the leg bars 32 and 33, which are also locked in substantially an upright position, the springs 54 acting to pull the brace straps 51 past the pivotal center 34 for this purpose. When the members 32 and 33 are lowered into bracing position the same springs serve to press these members downwardly on to the floor when the operator exerts a slight pressure on them to move them past the center 34 in the opposite direction, as clearly shown in Figures 3 and 4 of the drawings.

As the platform of the bed is lowered, the springs 55 and 56 serve to counterbalance the same, they being so disposed as to increase in tension as the foot end of the platform increases the leverage.

When it is desired to open the bed, first, the members 32 and 33 are lowered to the position shown in Figure 3. During this operation all of the springs assist in causing them to move downwardly after they have passed the vertical position.

The bed platform is next swung on its pivots 19 to a horizontal position as shown in Figure 5, it being counterbalanced throughout this operation by the springs as before mentioned. During this operation the springs 55 and 56 exert a straightening out strain on the toggle truss formed by the members 32 and 33 and the members 38, through the medium of the link members 47 and 51, thus imparting a downward pressure on the rollers 15 of the bed frame and holding them tightly pressed to the floor and lifting the rollers 16 off the floor, thereby giving to the frame a wide base sup-

port, and preventing the tilting of the same. During the lowering operation the members 44 are rocked on the pivots 48 to cause the bed head 41 to assume the position shown in Figure 5. The foot legs 29 are also swung into proper position during the lowering operation, to form a support for the foot end of the platform.

Having thus described my invention what I claim is:

1. A folding bed comprising a frame, a platform pivoted to said frame, a leg member pivoted to said frame, a brace bar pivoted at one of its ends to said leg member and slidably pivoted to said frame at its opposite end, a pair of link members pivoted together, one of said links having its end pivoted to said leg member, a head board member pivoted to said platform, a link brace strap member pivoted to said head board member and said frame and having its end extending beyond the pivotal point on said frame and pivoted to said pair of link members, a spring connected to said pair of link members and to said platform, and a spring connected to said pair of link members and to said leg member.

2. A folding bed comprising a frame, a platform pivoted to said frame, a leg member pivoted to said frame, a brace bar pivoted at one of its ends to said leg member and slidably connected to said frame at its opposite end, a pair of link members pivoted together at one end, the opposite end of one of said link members being pivoted to said leg member, the opposite end of the other link member being pivotally connected to said frame, and a spring connected to said platform and to said pair of link members.

3. A folding bed comprising a frame, a platform pivoted to said frame, a leg member pivoted to said frame, a brace bar pivoted at one of its ends to said leg member and slidably connected to said frame at its opposite end, a pair of link members pivoted together at one end, the opposite end of one of said link members being pivoted to said leg member, the opposite end of the other link member being pivotally connected to said frame, and a spring connected to said platform and to said pair of link members, and a spring connected to said pair of links and to said leg.

4. A folding bed comprising a frame, a platform pivoted to said frame, a leg member pivoted to said frame, a pair of link members pivoted together at one end, the opposite end of one of said link members being pivoted to said leg member, the opposite end of the other link member being pivotally connected to said frame, and a spring connected to said platform and to said pair of link members.

5. A folding bed comprising a frame, a platform pivoted to said frame, a leg mem-

ber pivoted to said frame, a pair of link members pivoted together, one of said links having one end pivoted to said leg member, a head board member pivoted to said platform, a link brace strap member pivoted to said head board member and said frame and having its end extending beyond the pivotal point on said frame and pivoted to the other link of said pair of link members, and a spring connected to said pair of link members and to said platform.

In testimony whereof I hereunto affix my signature.

FRANCIS S. INCO.
